UNITED STATES PATENT OFFICE

101,124

DESIGN FOR A PENCIL

Edwin C. Kubler, Hollis, N. Y., and Robert E. Friedlein, Mountain View, N. J., assignors to American Lead Pencil Company, Hoboken, N. J., a corporation of New York

Application May 8, 1936, Serial No. 62,555

Term of patent 7 years

To all whom it may concern:

Be it known that we, Edwin C. Kubler and Robert E. Friedlein, citizens of the United States, residing, respectively, at 186-40 Hillburn Avenue, Hollis, in the county of Queens and State of New York, and at 128 Lafayette Road, Mountain View, in the county of Passaic and State of New Jersey, have invented a new, original, and ornamental Design for a Pencil, of which the following is a specification, reference being had to the accompanying drawing, forming part thereof.

Figure 1 is a side view, Figure 2 is an enlarged view of the top part or tip, Figure 3 is a cross-section on line 3-3 of Figure 2, and Figure 4 is a cross-section on line 4-4 of Figure 2, of a pencil showing our new design.

The dominant feature of my design resides in the ferrule at the top of the pencil. The ferrule is square in cross section and has corners formed with an arcuate bead or tip, each of its faces being provided with a pair of circular openings spaced longitudinally so as to divide the faces into three sections of substantially equal widths and through which contrasting colors show.

We claim:

The ornamental design for a pencil, as shown and described.

EDWIN C. KUBLER.
ROBERT E. FRIEDEIN.
